(57) **CLAIM**

I claim the ornamental design for a dual light module, as shown and described.

DESCRIPTION

FIG. 1 is a perspective view of a dual light module according to my new design;

FIG. 2 is a left side elevational view of the dual light module of FIG. 1;

FIG. 3 is a top plan view of the dual light module of FIG. 1;

FIG. 4 is a bottom plan view of the dual light module of FIG. 1;

FIG. 5 is a front elevational view of the dual light module of FIG. 1;

FIG. 6 is a rear elevational view of the dual light module of FIG. 1;

FIG. 7 is a right side elevational view of the dual light module of FIG. 1;

FIG. 8 is a perspective view of another dual light module according to my new design;

FIG. 9 is a left side elevational view of the dual light module of FIG. 8;

FIG. 10 is a top plan view of the dual light module of FIG. 8;

FIG. 11 is a bottom plan view of the dual light module of FIG. 8;

FIG. 12 is a front elevational view of the dual light module of FIG. 8;

FIG. 13 is a rear elevational view of the dual light module of FIG. 8;

FIG. 14 is a right side elevational view of the dual light module of FIG. 8;

FIG. 15 is a perspective view of another dual light module according to my new design;

FIG. 16 is a left side elevational view of the dual light module of FIG. 15;

FIG. 17 is a top plan view of the dual light module of FIG. 15;

FIG. 18 is a bottom plan view of the dual light module of FIG. 15;

FIG. 19 is a front elevational view of the dual light module of FIG. 15;

FIG. 20 is a rear elevational view of the dual light module of FIG. 15; and,

FIG. 21 is a right side elevational view of the dual light module of FIG. 15.
